Patented Sept. 29, 1970

218,854

SNARE DRUM

Josephus B. Thompson, deceased, late of Covington, Ohio, by K. E. Stade, administrator, Covington, Ohio, assignor to Columbia Broadcasting System, Inc., New York, N.Y., a corporation of New York

Filed June 19, 1969, Ser. No. 17,826

Term of patent 14 years

Int. Cl. D17—04

U.S. Cl. D56—1

FIG. 1.

FIG. 2.

FIG. 3.

FIG. 4.

FIG. 1 is a perspective view illustrating a snare drum embodying the new design;

FIG. 2 is a side elevation thereof, as viewed from the lower-left in FIG. 1;

FIG. 3 is a bottom plan view thereof; and

FIG. 4 is a side elevation as viewed from the left in FIG. 2.

The side opposite the side shown in FIG. 2 is, except for the damper adjustment knob, substantially a mirror image of the side shown in FIG. 2.

What is claimed is:

The ornamental design for a snare drum, substantially as shown and described.
